UNITED STATES PATENT OFFICE.

MARTIN J. SHAUGHNESSY, OF AMSTERDAM, NEW YORK.

DESIGN FOR KNITTED FABRIC.

No. 37,754.

Specification for Design.

Patented Dec. 19, 1905.

Application filed October 14, 1905. Serial No. 282,857. Term of patent 7 years.

To all whom it may concern:

Be it known that I, MARTIN J. SHAUGHNESSY, a citizen of the United States, residing at Amsterdam, in the county of Montgomery and State of New York, have invented a new, original, and ornamental Design for Knitted Fabric, of which the following is a specification, reference being had to the accompanying drawing, forming part thereof.

The single figure of the drawing shows a plan view of a portion of a knitted fabric showing my new design.

I claim—

The ornamental design for a knitted fabric, as shown.

MARTIN J. SHAUGHNESSY.
